WILLIAM SHEAHAN, OF OREGON CITY, OREGON.

CLUTCH FOR SPOOLS OF PAPER-ROLLS.

1,123,146.

Specification of Letters Patent.

Patented Dec. 29, 1914.

Application filed January 27, 1912, Serial No. 673,938. Renewed July 2, 1914. Serial No. 848,103.

To all whom it may concern:

Be it known that I, WILLIAM SHEAHAN, a citizen of the United States, and a resident of Oregon City, Clackamas county, 5 State of Oregon, have invented a certain new and useful Improvement in Clutches for Spools of Paper-Rolls, of which the following is a specification.

This invention relates to a clutch, for 10 paper rolls, of the type heretofore invented by me and described in my pending application for Letters Patent of the United States, filed April 22, 1911, Serial Number 622,826, and my present invention has for its object 15 to obtain further improvements and benefits, the necessity of which I discovered since my said prior invention. Namely: in some printing presses the rolls of paper are unwound clockwise and in others they are 20 unwound in the opposite direction; hence in establishments happening to use both types of presses, it would necessitate the keeping on hand of right and left-hand clutches for the spools on which the roll of paper is 25 wound, unless the clutch used is adapted to operate properly with either type of press. Furthermore, where said two types of presses are used and a particular clutch must be used for each, it may happen, in the rush 30 of work, that the clutches are exchanged, and if the wrong clutch were used the press could not work, the roll of paper would have to be unmounted, and consequently causing considerable loss of time.

35 My invention therefore has for its direct purpose to so further improve my said clutch as to adapt it for use regardless of the direction in which the paper roll is to be rotated.

40 I attain my purpose by using, in place of my former sleeve and segmental wedges, a sleeve of which the periphery is formed to represent equal conical surfaces, with their larger faces abutting, and segmental wedges 45 formed with corresponding interior surfaces; the devices being preferably arranged as illustrated in the accompanying drawings, constituting a part of this specification.

50 In the drawings: Figure 1 is a sectional elevation of my clutch mounted on a shaft and arranged as in practice for clamping the paper spool on the shaft; Fig. 2 is a left-end elevation with respect to Fig. 1; 55 Fig. 3 is a top view of the arm of the nut and the adjustable lock-pin therein inserted;

Fig. 4 is a perspective detail of one of the segmental wedges employed by me; Fig. 5 is a diagrammatic view showing the abutting portions of two segmental wedges lying side by side and the insertion of the lock-pin between them, in order to connect the wedges with the nut by which the latter are set out and in; and Fig. 6 is a fragmental, 60 diagrammatic illustration of the mode of operation of my improved clutch. 65

The shaft *a*, is designed to be rotatably journaled at its ends in suitable bearings, not shown. It is formed with a flat face, *b*, so as to restrain the sleeve *c*, mounted thereon, against rotation. The sleeve, *c*, is of 70 uniform diameter at the end *d*, where it is provided with a peripheral thread, *e*, and the middle portion of the sleeve is formed with a series of double cone surfaces as *f*. The eye of the sleeve conforms to the peripheral contour of the shaft *a*, being provided with a flat surface as shown at *b'* in Fig. 2. On the threaded end, *e*, of the sleeve is mounted a nut *h*, which may be formed in two pieces, connected by bolts *h'* 75 inserted through ears *h''*, as shown in Fig. 2; such construction being necessary when the shaft, *a*, is formed with an integral collar, instead of a movable collar *w*, clamped in place by a set-screw *y*. The nut *h* is made with an annular flange *i*, formed 80 with an interior annular rib *j*.

g is the spool, preferably made of paper so as to obtain cheapness in manufacture and saving of freight. Within the spool *g* 90 are placed a series, for example, four, of segmental wedges *p*, having their inner faces formed with a series of double conical faces *p⁴*, *p⁵*, corresponding with the conical surfaces *f'*, *f²*, of the sleeve *c*; the conical 95 surfaces of the wedges being adapted to permit a slight longitudinal movement of the latter on the sleeve *c*, and causing the surfaces *p⁴* or *p⁵* of the wedges to climb up on and lock with the opposing surfaces *f'* 100 or *f²* of the sleeve *c*, as diagrammatically illustrated in Fig. 6. The segmental wedges *p* are respectively made at their left-hand extremity (with respect to their position in Figs. 1 and 4) with a flange *p³*, formed 105 with a circumferential groove *r*, corresponding with the inner rib *j* of the flange *i* of the nut *h*.

In order that my clutch will work properly, it is necessary that the cone surface 110 of the sleeve *c* and the related surfaces of

the segmental wedges p be accurately made, so that coöperating surfaces of said conical portions will represent true circles throughout their lengths. This construction is required in order to facilitate the climbing of the wedge segments on the cone surfaces of the sleeve c . Such action is accomplished by rotating the nut h in either direction, and by so doing longitudinally moving the wedge segments in corresponding direction on the sleeve c . For facilitating the rotation of the nut h it is formed with an integral arm i' , as shown in Figs. 1 and 2. In the arm i of the nut h is provided a lock-pin k , threaded on a cylindrical shank k' , which is formed with a flat head k^2 , on which is formed a circular head t . The arm i' is made with a cavity u , in which to receive the flat head k^2 of the lock-pin. At i^2 the arm i' is formed with an annular enlargement in which is seated the coil-spring m bearing against the shouldered portion k^3 of the lock-pin k .

The flanges p^3 of the wedge segments, p , at the abutting faces of the two segments lying side by side, are cut away, as illustrated at s in Figs. 4 and 5, so as to permit the lock-pin k to be projected between such two wedge segments, thereby connecting the nut with the segmental wedges. Should the manual rotation of the nut h on the sleeve c not accomplish the full expansion of the segmental wedges p , said lock-pin k will hold the wedge segments against rotation on the sleeve c , and the frictional contact between the outer faces of the wedge segments and the core of the spool will hold the clutch against rotation in the spool. The lock-pin k is released by lifting it against the tension of the coil-spring m and so arranging it that the web k^2 will be seated crosswise of instead of in the cavity u , therefor provided in the arm i' . The sleeve c and the wedge segments may move each on the other; but, by reason of the greater friction being imposed upon the outer faces of the segmental wedges, in contact with the spool q , the sleeve c does all the traveling to and fro on the shaft a , during the operation of tightening and releasing the spool. The conical surfaces of the sleeve and the segmental wedges are arranged at a steep inclination, in short steps, so that a single turn of the nut h causes maximum expansion of my clutch. The clutch is in the first instance thrown manually by rotating the nut h ; and if, afterward, during service, the wedge-element should become loose and rotate on the sleeve, the clutch will be automatically retightened by reason of the nut being locked with the wedge-element and caused to ro-

tate therewith, thus moving the sleeve, c , relatively longitudinally and again tightening the clutch.

I claim:

1. In a clutch element of the character described, a sleeve adapted to be mounted on a shaft, means for holding said sleeve against rotating on the shaft, one end of said sleeve being threaded and the other formed with a series of peripheral, contiguous, conical surfaces, tapered in opposite directions, said conical surfaces being of short length and their tapered faces of steep inclination; a segmental wedge having corresponding conical surfaces, said segmental wedge being adapted for being mounted on the sleeve and the abutting conical surfaces adapted to permit the segmental wedge relative longitudinal movement on the sleeve; a nut on the threaded end of the sleeve; and means for connecting the segmental sleeve with the nut so as to rotate together.

2. In a clutch of the character described comprising a sleeve adapted to be mounted on the shaft and segmental wedges adapted for being mounted on the sleeve, the abutting faces of the sleeve and the wedge formed with conical surfaces, said sleeve having one end threaded, the segmental wedges provided at the corresponding end with a peripheral groove, a nut mounted on said threaded end of the sleeve, said nut made with a peripheral flange adapted for being seated in said groove of the wedge segment; said nut made of divisible parts and having means for fastening its parts together; and means for locking one of the segmental wedges with the nut, so as to rotate therewith.

3. In a clutch of the character described comprising a sleeve adapted to be mounted on the shaft and segmental wedges adapted for being mounted on the sleeve, the abutting faces of the sleeve and the wedge formed with conical surfaces, said sleeve having one end threaded, the segmental wedges provided at the corresponding end with a peripheral groove, a nut mounted on said threaded end of the sleeve, said nut made with a peripheral flange adapted for being seated in said groove of the wedge segment; a spring-controlled pin adapted for being projected between two adjacent wedge segments; and means for holding said pin retracted from between the wedge segments.

WILLIAM SHEAHAN.
